CLAIM

The ornamental design for a ceiling light as shown and described.

DESCRIPTION

FIG. 1.1 is a perspective view of a ceiling light, accordance to my design;

FIG. 1.2 is a top view thereof;

(Continued)

FIG. 1.3 is a right view thereof;
FIG. 1.4 is a front view thereof.

The broken lines in the drawings are for the purpose of illustrating environmental structure and forms no part of the claimed design.
